CURTAIN SUSPENDER

Filed Jan. 11, 1922

Inventor
J. R. E. Heseltine,
By Marks Clerk
Atty's.

UNITED STATES PATENT OFFICE.

JOSEPH RICHARD EWART HESELTINE, OF BIRMINGHAM, ENGLAND, ASSIGNOR TO
RICHARD ARTHUR TAUNTON, OF HAWKINGE, KENT, ENGLAND.

CURTAIN SUSPENDER.

Application filed January 11, 1922. Serial No. 528,533.

To all whom it may concern:

Be it known that I, JOSEPH RICHARD EWART HESELTINE, a subject of the King of Great Britain and Ireland, residing at 116 5 Branston Street, in the city of Birmingham, England, have invented certain new and useful Improvements Relating to Curtain Suspenders, of which the following is a specification.

10 This invention has for its object to provide an improved curtain suspender.

In the accompanying sheet of explanatory drawings:—

15 Figure 1 is a side elevation of a curtain suspender constructed in accordance with this invention.

Figure 2 is an end elevation of the same.

In carrying the invention into effect a pair of similar claws *a* are made of semi-circular or other convenient shape. These are hinged together at one end and arranged to form a loop, the adjacent ends of the claws, which are pointed, being caused to overlap. To the pivoted end of one of the 20 claws, an integral extension in the form of a hook *b* is provided for engaging the eye of an ordinary curtain ring. The claws are produced by stamping operations on thin sheet metal and secured by a hollow 25 pivot piece *c*. The claws may be embossed or otherwise treated to increase their stiffness.

When in use the claws are caused to enter opposite sides of the curtain, the material 30 of the latter being thus held between the claws. Both ends of the claws penetrate the curtain, and consequently a pull on the curtain only increases the security of the fastening. The dotted lines in Figure 1 35 show one of the claws opened out relatively to the other to permit their attachment to a curtain.

In the construction shown in Figures 3 and 4 each claw *a* is formed with an integral extension *d*, the two parts *d* being similar in form to the parts *a*. As in the first form the parts *a* grip the curtain, and

the parts *d* engage a curtain rod, ring or the like from which the curtain is suspended. The dotted lines show one of the parts 50 *a* *d* opened out relatively to the other.

By this invention I am able to obviate the well known inconvenience of the usual safety pins by which curtains are ordinarily suspended.

Having thus described my invention what I claim as new and desire to secure by Letters Patent is:

A curtain suspender including a flat sheet metal jaw member having opposite 60 plane side surfaces parallel from end to end, the intermediate portion of said member being of enlarged area to form a pivot receiving body, one end portion of the member being shaped to form a hook and the 65 other end portion being shaped to form a claw terminating in a sharp point adapted to readily penetrate a curtain, the claw being of arc shape and extending greater than a semicircle, a second flat sheet metal 70 member having plane opposite side surfaces parallel from end to end, one of the plane surfaces of the first member abutting against one of the plane surfaces of the other member, a portion of the second member 75 being of enlarged area to form a pivot receiving body, said second member also having a portion shaped to form a claw terminating in a sharp point adapted to readily penetrate a curtain, the last mentioned 80 claw being of arc-shape and extending greater than a semicircle, a pivot pin connecting the body portions of said members and permitting angular movement of the members independently of one another, and 85 the pointed ends of the claw portions extending in opposite directions and being inturned and upwardly recurved so as to pierce and grip between them the fabric of the curtain.

90 In testimony whereof I have signed my name to this specification.

JOSEPH RICHARD EWART HESELTINE.
